UNITED STATES PATENT OFFICE

135,427

DESIGN FOR A PIN OR SIMILAR ARTICLE

Volney L. Reid, Rutherfordton, N. C.

Application July 18, 1942, Serial No. 107,603

Term of patent 3½ years

To all whom it may concern:

Be it known that I, Volney L. Reid, a citizen of the United States, residing at Rutherfordton, in the county of Rutherford and State of North Carolina, have invented a new, original, and ornamental Design for a Pin or Similar Article, of which the following is a specification, reference being had to the accompanying drawing, forming part thereof.

Figure 1 is a front elevational view of a pin or similar article showing my new design, and

I claim:

The ornamental design for a pin or similar article, as shown.

VOLNEY L. REID.
